(57) **CLAIM**

I claim the ornamental design for a faux window assembly, as shown and described.

DESCRIPTION

FIG. 1 is a perspective view showing a front, top and side of a first embodiment of the faux window assembly;

FIG. 2 is a front elevational view of the first embodiment of the faux window assembly;

FIG. 3 is a rear elevational view of the first embodiment of the faux window assembly;

FIG. 4 is an elevational view of a first side of the first embodiment of the faux window assembly;

FIG. 5 is an elevational view of a second side of the first embodiment of the faux window assembly;

FIG. 6 is a top plan view of the first embodiment of the faux window assembly;

FIG. 7 is a bottom plan view of the first embodiment of the faux window assembly;

FIG. 8 is a perspective view showing a front, top and side of a second embodiment of the faux window assembly;

FIG. 9 is a front elevational view of the second embodiment of the faux window assembly;

FIG. 10 is a rear elevational view of the second embodiment of the faux window assembly;

FIG. 11 is an elevational view of a first side of the second embodiment of the faux window assembly;

FIG. 12 is an elevational view of a second side of the second embodiment of the faux window assembly;

FIG. 13 is a top plan view of the second embodiment of the faux window assembly; and,

FIG. 14 is a bottom plan view of the second embodiment of the faux window assembly.

The dashed lines and broken lines are for purposes of illustrating environmental structure and form no part of the claimed design.

1 Claim, 8 Drawing Sheets
